AUTOMOTIVE VEHICLE WINDOW REGULATOR HANDLE

Glenford M. Haviland, Royal Oak, Mich., assignor
to General Motors Corporation, Detroit, Mich.,
a corporation of Delaware

Application October 28, 1949, Serial No. 5,751

Term of patent 7 years

(Cl. D10—8)

To all whom it may concern:

Be it known that I, Glenford M. Haviland, a citizen of the United States, and a resident of Royal Oak, State of Michigan, have invented a new, original, and ornamental Design for an Automotive Vehicle Window Regulator Handle, of which the following is a specification, reference being made to the accompanying drawing, forming a part thereof.

In the drawing:

Figure 1 is a plan view of an automotive vehicle window regulator handle, showing my new design.

Figure 2 is a side elevation thereof.

Figures 3 and 4 are sectional views taken on lines 3—3 and 4—4 of Figures 2 and 1, respectively.

I claim:

The ornamental design for an automotive vehicle window regulator handle, substantially as shown.

GLENFORD M. HAVILAND.
